UNITED STATES PATENT OFFICE

OSWALD I. GROTTÉ, OF HUNTER, NORTH DAKOTA

HASP

Application filed June 24, 1931. Serial No. 546,633.

This invention relates to certain new and useful improvements in hasps and the primary object of this invention is to provide means for retaining the hasp against casual 5 unlatching, and to thereby retain the door or closure tightly closed at all times.

In the types of hasps now used, there is always present slight play between the hasp plate and the keeper, thus permitting the 10 door to swing slightly ajar creating drafts, rendering the use of hasps objectionable.

I overcome the above objection, through an arrangement of parts, embodied in the hasp construction as will be best apparent from 15 a study of the following description, taken in connection with the accompanying drawings wherein:

Figure 1 is an elevational view of a hasp embodying the features of the present invention, the same being shown as applied to a door or closure.

Figure 2 is a plan view thereof.

Figure 3 is a perspective view of the hinge plate of the hasp constructed in accordance 25 with the present invention.

With reference more in detail to the drawings, it will be seen that I have applied the invention to a conventional type of hasp and one that is well known in the art. The hasp, 30 as shown, includes the usual attaching or hinge plate 5 to which is hinged at one end as at 6, the hasp plate 7 that at its free end is provided with the usual slot or aperture 8 through which the head 9 of a keeper 10 is 35 passed, so that when the head 9 is subsequently rotated to the position shown in Figure 1, the head contacts the outer face of the hasp 7 thus retaining the door or closure in a closed position.

40 In actual practice and as is well known in the art, the plate 5 is suitably secured to the door or closure D, and the attaching plate or body portion of the hasp is suitably secured to the wall or door jam B.

45 In the type of hasp shown, the keeper usually is of swivel type to permit the rotation of the head thereof as and for the purpose above explained, and as shown in Figure 2 there is considerable space or clearance between the head 9 and the base plate of the

keeper thus leaving the free end of the hasp plate 7 free to move between the head 9 and the base plate of the keeper so that a gust of wind acting on the door or closure D causes the same to swing slightly ajar thus permitting draft. 55

To overcome this objectionable feature, I propose to provide, preferably adjacent the free end of the plate 5, a projection 11 transversing the plate and projecting from the plate a sufficient distance to compensate for the clearance between the head 9 and the base plate of the keeper as will be apparent from a study of Figure 2, so that when the head 9 is rotated to the position shown in Figure 1, the inward swinging movement of the plate 7 being limited by the projection 11, the head 9 will bind against an adjacent portion of the hasp plate 7 with the result, that the hasp plate 7 will be effectively held 70 against any swinging movement about its hinge 6 and consequently the door D will be retained in a securely closed position. 65

As shown in Figure 3, the projection 11 is preferably formed by flanging said end of the plate 5, that is, by bending the plate at substantially right angles to itself as shown. 75

Even though I have herein shown and described the preferred embodiment of the invention, it is to be understood that the same 80 is susceptible of further changes, modifications and improvements coming within the scope of the appended claim.

Having thus described my invention, what I claim as new is:

85 A hasp including in combination a hinge plate, a hasp plate hinged thereto, and said hinge plate being provided with a non-yielding projection extending laterally therefrom and against which said hasp plate abuts when the latter is swung into position for engagement with a keeper.

In testimony whereof I affix my signature.

OSWALD I. GROTTÉ.
